(57) **CLAIM**

The ornamental design for a heel for shoe, as shown and described.

DESCRIPTION

FIG. 1 is a perspective view of a heel for shoe, showing our new design;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a perspective view of another embodiment thereof;

FIG. 9 is a front view thereof;

FIG. 10 is a rear view thereof;

FIG. 11 is a side view thereof;

FIG. 12 is an opposite side view thereof;

FIG. 13 is a top view thereof; and,

FIG. 14 is a bottom view thereof.

Broken lines are used in the drawings to illustrate environment which forms no part of the claimed design.

1 Claim, 14 Drawing Sheets
